UNITED STATES PATENT OFFICE.

ROBERT HOWARD BIGGS, OF ST. CATHARINES, ONTARIO, CANADA.

GARTER.

Application filed May 14, 1924. Serial No. 713,303.

To all whom it may concern:

Be it known that I, ROBERT HOWARD BIGGS, a subject of the King of Great Britain, and a resident of the city of St. Catharines, in the county of Lincoln, in the Province of Ontario, Canada, have invented certain new and useful Improvements in Garters, of which the following is the specification.

10 My invention relates to improvements in garters, and the object of the invention is to devise a garter which is not readily subject to wear, in which elastic fabric is dispensed with and loss of resilience incident 15 to the employment of such fabric obviated, and which will therefore have a maximum life, and it consists essentially of the arrangement and construction of parts hereinafter more particularly described.

20 Fig. 1 is a general view showing my garter applied to the leg of a wearer.

Fig. 2 is an enlarged perspective detail of the main actuating portion of my garter.

Fig. 3 is a sectional view through Fig. 2.

25 Fig. 4 is a perspective detail of the rear pad forming the body of my garter.

Fig. 5 is a perspective detail of the front pad forming the body of my garter.

30 Fig. 6 is a sectional view on line 6-6, Fig. 2.

Fig. 7 is a perspective detail of the anti-friction plate which is secured to the front pad illustrated in Fig. 5.

35 In the drawings like characters of reference indicate corresponding parts in each figure.

The body of my garter comprises a front pad 1, and a rear pad 2, which are sewn together by lines of stitching 3'.

40 The front pad 1 is provided with an orifice 1^x and a slotted arc shaped opening 1°, for a purpose which will hereinafter appear.

The rear pad 2 is provided with a tongued 45 extension 2^x to which are secured dome fasteners 2°, for a purpose which will hereinafter appear.

3 is a spring, the body of the spring being formed annular and preferably of 50 round tempered wire, having the ends 3^x and 3° overlapping as clearly indicated in Fig. 2.

The outer extremities of the ends 3^x and 3° are turned radially outward to form arms 55 4 and 5, the extremities of which are out-turned, as indicated at 6 in Fig. 3.

The body of the spring formed by the annular portion 3 is placed between the pads 1 and 2 and secured therebetween by stitching 7 in proximity to the bottom portion of the body. The radial arms 4 and 5 extend upward between the pads, the arm 4 extending to the orifice 1^x so that the out-turned portion 6 of the arm extends through such orifice and protrudes beyond the front 65 face of the pad 1, the extreme outer end of the arm being provided with a knob or other enlargement 8.

The arm 5 is provided in proximity to its base with a slightly off-set portion 5^x to 70 enable the arm to pass through the slotted opening 1° so that the major portion of the arm 5 is located at the outside of the front pad 1.

The out-turned portion 6 of the arm 5 is 75 provided with a knob 9.

10 is a band of inelastic fabric provided with metal loops 11 and 12 at its free ends, such loops being of common construction and provided centrally with slotted tongues 80 8^x and 9^x with which the knobs 8 and 9 engage in the usual manner.

13 is a tab which is secured around the annular spring body 3 between the pads 1 and 2 so as to depend downward from the bottom of the pad, as illustrated in Figs. 1 and 2, such tab being provided with a fastener or clip 14 of usual construction and comprising a knob 16 which is inserted beneath the edge of the stocking 17^x the enlarged portion of the loop 15 being passed over the knob and then drawn upward so that the neck portion of the knob is drawn in to the narrowed lower portion of the loop so as to clip the stocking fabric around 90 the knob in the usual manner.

The metal loop 11 is passed over the knob 8 which protrudes from the front face of the pad 1, and is then drawn upward in an inclined direction so that the neck of the knob 8 enters the narrowed portion of the slotted tongue 8^x. The corresponding end of the band 10 is then detachably secured to the tongue extension 2^x by means of the dome fastener members 2° and 10°, to securely connect the corresponding end of the band 10 to the garter body formed by the pads 1 and 2.

The band 10 is then passed around the leg of the wearer and the loop 12 is engaged 110 with the knob 9 when in the position shown by dotted lines in Fig. 2, the free end

- of the arm 5 being pushed over by the finger of the wearer to bring it into engagement with the loop. When the arm 5 is released by the finger, such arm exerts on the band the required tension to give it the desired elasticity. By this means a resilient connection is formed so that there will be an elastic give to the garter when on the leg of the wearer.
- 10 In order to prevent the movement of the arm 5 as it plays to and fro, due to the movement of the wearer, wearing out the face of the pad 1, I provide an anti-friction plate 17 which is provided with edge slots 18 and 19 through which stitches 20 and 21 extend to secure the plate to the front pad 1. The arm 5 plays backwards and forwards upon the face of this plate, thereby relieving the wear thereof from the pad.
- 15 20 In order to prevent the pull upon the arm 5 exceeding the strength of the spring, I provide a stop rib 22 against which the arm 5 is finally drawn when a maximum pull is exerted thereon.
- 25 30 From this description it will be seen that I have devised a garter in which the employment of an elastic band liable to quickly lose its elasticity is dispensed with, and by which I am enabled to employ an inelastic fabric which will not readily wear out and yet provide means whereby the garter is resiliently held round the leg of the wearer so as to give and take with the movement of the leg, expanding and contracting as required by such movement.
- What I claim as my invention is:
1. A garter comprising a body consisting of a front and rear pad secured together round their edges and having a perforation 40 in the upper portion of the front pad at one side of the centre and an arc shaped slotted opening in the lower portion of the pad towards the opposite side of the centre, a spring secured between the members of 45 the body having diverging arms extending outward from the point of attachment, one of such arms having an out-turned portion extending through the orifice of the front pad, and the other arm provided with an off-set portion extending through the slotted opening of the front pad, and an inelastic band adapted to extend around the leg of the wearer, and detachable connecting means between the ends of the band and the 50 arms of the spring.
2. A garter comprising a body consisting of a front and rear pad secured together around their edges and having a perforation 60 in the upper portion of the front pad at one side of the centre and an arc shaped slotted opening in the lower portion of the front pad towards the opposite side of the centre, a spring secured between the members of the body having diverging arms extending outward from the point of attachment, one of such arms having an out-turned portion extending through the orifice of the front pad, and the other arm provided with an off-set portion extending through the slotted opening of the front pad, and an inelastic band adapted to extend around the leg of the wearer, and detachable connecting means between the ends of the band and the arms of the spring.

tending upward from the point of attachment, one of such arms having an out-turned portion extending through the orifice of the front pad and the other arm provided with an off-set portion extending through the slotted opening of the front pad, an inelastic band adapted to extend around the leg of the wearer, detachable connecting means between the ends of the band and the arms of the spring, and an anti-friction shield secured to the outer face of the front pad against which the movable arm of the spring has movement.

3. A garter comprising a body consisting of a front and rear pad secured together around their edges and having a perforation in the upper portion of the front pad at one side of the centre and an arc shaped slotted opening in the lower portion of the pad towards the opposite side of the centre, a spring secured between the members of the body having diverging arms extending outward from the point of attachment, one of such arms having an out-turned portion extending through the orifice of the front pad and the other arm provided with an off-set portion extending through the slotted opening of the front pad, an inelastic band adapted to extend around the leg of the wearer, detachable connecting means between the ends of the band and the arms of the spring, an anti-friction shield secured to the outer face of the front pad against which the movable arm of the spring has movement, and means carried by the shield for limiting the outward movement of the movable arm.

4. A garter comprising a body consisting of a front and rear pad secured together round their edges and having a perforation in the upper portion of the front pad at one side of the centre and an arc shaped slotted opening in the lower portion of the body towards the opposite side of the centre, a spring secured between the members of the body having diverging arms extending outward from the point of attachment, one of such arms having an out-turned portion extending through the orifice of the front pad, and the other arm provided with an off-set portion extending through the slotted opening of the front pad, and an inelastic band adapted to extend around the leg of the wearer, detachable connecting means between the ends of the band and the arms of the spring, an anti-friction shield secured to the outer face of the front pad against which the movable arm of the spring has movement, and a rib extending outward from the shield against which the movable spring arm is drawn when at the limit of its outward movement.
